UNITED STATES PATENT OFFICE.

CHARLES R. HOWARD AND RICHARD W. WAGNER, OF WORCESTER, MASSACHUSETTS,
ASSIGNORS TO CROMPTON & KNOWLES LOOM WORKS, OF WORCESTER, MASSA-
CHUSETTS, A CORPORATION OF MASSACHUSETTS.

COLOR INDICATION FOR MULTICOLOR WEFT-REPLENISHING LOOMS.

Application filed October 8, 1926. Serial No. 140,352.

This invention relates to multi-color weft replenishing looms and it is the principal object of the invention to provide a simplified color control for the magazine or weft 5 replenishing mechanism.

In weft replenishing looms employing two or more boxes it is necessary to have the magazine coordinated with the active shuttle so that the color selector may choose a bobbin of the proper color to be introduced into the exhausted shuttle. It has been proposed heretofore to keep the color selector of the magazine in time with the active shuttle in worsted looms by a direct connection 10 with the chain which is attached to the box lifter rod. The comparatively slow speed of the worsted loom makes this type of indication possible, but it will be seen that it is necessary for the boxes to come completely 15 to rest before the color indicator can operate. On gingham looms this type of indication is found to be too slow and there are accordingly used rotating cams which give the indication in advance of the completion 20 of the motion of the boxes. This latter type of motion is found satisfactory on two and four box looms but the compounding of the levers incident to such construction is found to involve considerable mechanism 25 when applied to a six box loom, and it is an important object of our invention to provide a simple movable member having an indicating surface to correspond with each shuttle and movable with the boxes in a single plane so as to occupy very little space, 30 each indicating surface being provided with a dwell and the dwells being separated by inclined or cam faces which move the color indicator to its proper position prior to the arrival 35 of the boxes at their final position, this latter construction permitting a relatively higher rate of speed of the loom than would be possible if no dwell were used.

It is a further and more specific object 40 of our invention to provide a sliding and multi-faced cam operatively connected with the box rod, the cam moving in a straight line and being so connected to the box rod as not to partake of the swaying motion of the latter as the lay moves back and forth.

It is a further object of our invention to 45 provide a multi-faced cam to position the color selector wherein the cam derives its movement from the box lifting lever so as to

share all the movements of the latter and to 55 assume as many different operative positions as there are boxes.

In the slow running worsted looms previously mentioned the indication for the color slide is derived from the chain which 60 is attached to the box lifter rod. It not infrequently happens that a shuttle will not be properly boxed just prior to the shifting of the boxes so that the latter will be held against sliding movement. Under these conditions 65 the color slide will be held against movement by an improperly placed shuttle and a misindication to the magazine may result. It is a further object of our invention to connect the color slide directly to 70 the box lifter lever so that although the connection normally employed between the lever and the box lifter rod yield when a shuttle is misplaced the color slide will nevertheless receive a complete movement due to the 75 fact that the box lifter lever always receives a complete motion.

With these and other objects in view which will appear as the description proceeds, our invention resides in the combination and 80 arrangement of parts hereinafter described and set forth in the claims.

In the accompanying drawings wherein we have shown a convenient embodiment of 85 our invention,

Fig. 1 is a side elevation of a loom having our invention applied thereto, the boxes being indicated in section and a portion of the box motion being shown diagrammatically,

Fig. 2 is an enlarged horizontal section on line 2—2 of Fig. 1, showing the compound levers for moving the boxes in top plan view,

Fig. 3 is an enlarged detail front elevation 95 of the lower part of the cam showing the manner in which the same is mounted,

Fig. 4 is an enlarged horizontal section on line 4—4 of Fig. 1,

Fig. 5 is an enlarged section on line 5—5 100 of Fig. 4,

Fig. 6 is an enlarged vertical section on line 6—6 of Fig. 1, showing the connection between the box lifter lever and the two links associated therewith, and

Fig. 7 is an enlarged side elevation of a portion of the color slide controlling cam showing the relation of the dwell portions 105

thereof with respect to the roll when the boxes have completed their shifting movement.

Referring particularly to the drawings it will be seen that we have provided a loom-side 10 having a bottom shaft 11 on which is mounted a master gear indicated diagrammatically at 12. Three pinions 13, 14, and 15 are spaced around the master gear 12 and are adapted to be in mesh therewith according to the demands of the box motion and under control of a pattern chain (not shown). These pinions are each provided with upwardly extending links 16 one of which is connected as at 17 to the end of the box lever 18 and the other two of which are connected as at 19 to the opposite ends of a lever 20 mounted on a stud 21 secured to the box lever 18. The stud 21 has engagement with an arm 22 pivoted as at 23 to a fixed part of the loom. The box lifting lever 18 is therefore supported at two points one of which is given three positions by the pinions 13 and 15 and the other of which is given two positions by the other pinion. By reason of this mechanism the right hand end of the lever 18 as viewed in Fig. 1 is given six different positions under control of the pattern mechanism.

The forward end of the lever 18 is operatively connected as at 24 to a depending link 25 pivotally and yieldingly connected as at 26 on a box lifter rod 27 the upper end of which supports a multi-cell box 28 in this instance shown as adapted to receive six different shuttles. The form of box motion described herein is well-known and may be of the usual so-called Crompton type.

The weft replenishing mechanism which is located at that side of the loom opposite the box motion comprises a stand 30 on which are mounted for vertical reciprocation six slides 31, one for each shuttle. Said slides are provided with laterally extending lugs 32 which cooperate with a color slide 33 mounted on a rod 34 slidably mounted in spaced bearings 35 formed on the stand 30. A collar 36 fixed to the rod 34 has operative connection with the upper end of a bell crank lever 37 pivoted as at 38 to a part of the stand 30. A spring plunger 39 interposed between a part of the lever 37 and a fixed part of the stand tends to move the rod 34 normally to the left.

By means of mechanism not shown herein the color slide 33 is given an operative angular movement with respect to the vertical slides 31 and is so related to the latter that but one slide will be moved at a time, namely, the slide which corresponds to the shuttle which is to be replenished. That part of the mechanism relating to the automatic feature and mounted on stand 30 may be substantially the same as set forth in patent to Ryon No. 1,030,748.

Our present invention relates more particularly to the devices interposed between the box rod 27 and the lever 37 to position the color slide 33 correctly with respect to the slides 31. In carrying our improvements into effect we connect the rearwardly extending arm 40 of lever 37 to a depending connector 50, the lower end of which is connected to an arm 51 secured to a rocker shaft 52 which extends across the loom, that end 75 of the rocker shaft adjacent the box motion end of the loom having secured thereto a second arm 53, the upper end of which is adjustably connected to a rod 54. The forward end of said rod is operatively connected as at 55 to a slide 56 shown more particularly in Fig. 4, said slide passing through guide bearings 57 carried by a bracket 58 secured to the loomside 10 as indicated in Fig. 4. The forward end of the slide 56 is 80 forked and provided with a pin 59 on which is mounted for free rotation a hardened roll 60 of a radius preferably less than the distance between the center of pin 59 and the forward end of the slide 56.

Motion is imparted to the slide 56 by means of a multi-faced cam 61 having a series of dwells 62 connected by intervening cam faces 63, said cam being formed as shown in Figs. 1, 3, and 4, and having the upper portion thereof formed with a thin web 64 and having the forward vertical portion thereof formed with a guide flange 65.

In order to guide the cam the bracket 58 is provided with a depending arm 66 provided with a vertically extending notch 67 which receives one side of flange 65. The other side of the flange is received in pockets 68 defined by a rear vertical wall of the arm 66 and clips 69 secured to the bracket by bolts 70. The pockets 67 and 68 house the flange 65 and guide the same for vertical movement.

The lower end of cam 61 is provided with a foot 71 pivotally connected as at 72 to an upwardly extending link 73 and said link is pivotally connected to the stud 24 carried by the box lifting lever 18 in a manner similar to that indicated in Fig. 6. As indicated in said figure the stud receives the upper end of connector 25 and is provided with a shoulder 74 which bears against one side of the box lifting lever 18. The stud extends through the lever 18 and has a reduced portion 75 on which is mounted a spacing collar 76. A washer 77 is held against the collar 76 by nut 78 and the upper end of link 73 has an opening which receives the collar 76, the thickness of the upper part of said link 73 being slightly less than the thickness of collar 76. By means of the structure shown in Fig. 6 both the links 25 and 73 will be moved vertically with the box lever 18 and slight back and forth movements of the stud 24 due to the rocking of 130

lever 18 about its various centers will not be communicated to the multi-faced cam 69 because of the link 73, said link imparting vertical motion to the cam without requiring the same to partake of the motions either of the box lifting lever or the box rod.

In operation, spring plunger 39 will hold the roll 60 against one or another of the faces of the cam 61, said roll being in contact with the lowest dwell portion 62 of the cam as shown in Fig. 1. When the boxes shift the cam 61 will move vertically with the boxes so that the roll 60 will be displaced horizontally by one or another of the dwells 62, depending upon which box is active. The motion of the slide 56 will be communicated to the lever 37 and the latter in turn will position the color slide 33 to register with the slide 31 corresponding to the active shuttle.

Referring to Fig. 7 it will be seen that the dwells 62 and cam faces 63 are so located that when the boxes have completed their shifting movement the roll 60 will be in contact with the mid-portion of one or another of the dwells 62. When shifting from one position to another the roll 60 will come to its final position in advance of the boxes so that the color slide 33 will be accurately positioned with respect to the slides 31 before the boxes come to rest, the purpose of this construction being to permit an early rocking of the color slide 33 as set forth in the aforesaid Patent No. 1,030,748.

From the foregoing it will be seen that we have provided a very simple mechanism for imparting a comparatively large number of movements to the color slide 33, said mechanism including a multi-faced cam movable by a connection with the box lifting lever. It will further be seen that the cam is so connected that although the same moves bodily it can be guided to have a right line movement and not partake of the oscillations of the box lifting lever 18, this result being accomplished by the link 73. Furthermore, it will be seen that the dwells permit the roll 60 and therefore the color slide 33 to come to rest before the boxes complete their shifting movement, the advantage of this construction being that the color slide can be given an operative movement before the boxes come to rest, thus gaining the time necessary when the loom is running at a comparatively high rate of speed. While the multifaced cam has been described as having a right line movement, yet we do not wish to be limited to this construction, and it is further to be understood that the type of box motion illustrated herein is for illustrative purposes only and that we do not wish to be limited to this particular form of device for raising and lowering the boxes.

Furthermore, it will be seen that the color

indication will be given to the magazine properly even though the box lifter rod be held against movement by an improperly boxed shuttle.

Having thus described our invention it will be apparent that changes and modifications may be made therein by those skilled in the art without departing from the spirit and scope of the invention, and we do not wish to be limited to the details herein disclosed, but what we claim is:

1. In a weft replenishing mechanism having a plurality of shifting shuttle boxes and a weft replenishing mechanism provided with a color slide to select a proper bobbin for the exhausted shuttle, a box lifting lever operatively connected to the boxes, a multi-faced cam operatively connected to and deriving its movement from the box lifting lever, and connections between the multi-faced cam and the color selector on the weft replenishing mechanism to position the latter in any one of a number of positions equal to the number of boxes.

2. In a weft replenishing mechanism having a plurality of shifting shuttle boxes and a weft replenishing mechanism provided with a color slide to select a proper bobbin for the exhausted shuttle, a box lifting lever operatively connected to the boxes, a multi-faced cam operatively connected to and deriving its movement from the box lifting lever and capable of assuming as many different positions as there are boxes, and operative connections between the multi-faced cam and the color selector to give to the latter as many different positions as there are boxes.

3. In a weft replenishing mechanism having a plurality of shifting shuttle boxes and a weft replenishing mechanism provided with a color slide to select a proper bobbin for the exhausted shuttle, a box lifting lever operatively connected to the boxes, a multi-faced cam operatively connected to and deriving its movement from the box lifting lever, said cam having a plurality of dwells spaced by cam faces, an actuator for the color slide having operative contact with the slide and normally contacting with one of the dwells at substantially the mid point thereof when the boxes are at rest, and operative connections between the actuator and the slide.

4. In a weft replenishing mechanism having a plurality of shifting shuttle boxes and a weft replenishing mechanism provided with a color slide to select a proper bobbin for the exhausted shuttle, a box lifting lever operatively connected to the boxes, a multi-faced cam mounted on the loom for right line movement and operatively connected to and deriving its motion from the box lifting lever, and connections from the cam to the color slide to impart to the latter a

plurality of positions equal in number to the number of boxes.

5. In a weft replenishing mechanism having a plurality of shifting shuttle boxes and a weft replenishing mechanism provided with a color slide to select a proper bobbin for the exhausted shuttle, a box lifting lever operatively connected to the boxes, a multi-faced cam operatively connected to and deriving its motion from the box lifting lever, fixed guides along which the cam slides, a slide guided for movement transverse to the path of movement of the multi-faced cam, said slide being in contact with one or another of the faces of the cam, and connections between the slide and the color selector of the weft replenishing mechanism, whereby the multi-faced cam moves the color selector to any one of a plurality of positions depending upon the position of the multi-faced cam.

6. In a weft replenishing mechanism having a plurality of shifting shuttle boxes and a weft replenishing mechanism provided with a color slide to select a proper bobbin for the exhausted shuttle, a box lifting lever operatively connected to the boxes, a multi-faced cam operatively connected to and deriving its motion from the box lifting lever, an actuator for the color slide, and a single resilient means operatively connected to the color slide of the weft replenishing mechanism and the actuator therefor, said resilient means tending to hold the actuator in yielding contact with the faces of the multi-faced cam, and connections between said actuator and the color slide of the weft replenishing mechanism.

In testimony whereof we have hereunto affixed our signatures,

CHARLES R. HOWARD.
RICHARD W. WAGNER.
